US0D1061974S

(12) **United States Design Patent** (10) **Patent No.:** **US D1,061,974 S**
(45) **Date of Patent:** **** Feb. 11, 2025**

(54) **PORTABLE LIGHT**

(71) Applicant: **STREAMLIGHT, INC.**, Eagleville, PA (US)

(72) Inventors: **Raymond L. Sharrah**, Collegeville, PA (US); **Cleatis A. Eichelberger**, East Norriton, PA (US)

(73) Assignee: **Streamlight, Inc.**, Eagleville, PA (US)

(**) Term: **15 Years**

(21) Appl. No.: **29/802,199**

(22) Filed: **Aug. 3, 2021**

(51) **LOC (15) Cl.** **26-02**

(52) **U.S. Cl.**

USPC **D26/39**

(58) **Field of Classification Search**

USPC D26/37, 39, 34, 38

CPC F21L 4/00; F21V 21/084; F21V 21/0885

See application file for complete search history.
